(57) **CLAIM**

The ornamental design for a toy, as shown and described.

DESCRIPTION

FIG. 1 is a first perspective view of a toy showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view thereof, shown disassembled for completeness of illustration; and,

FIG. 10 is another exploded perspective view thereof, shown disassembled for completeness of illustration.

The broken lines shown in the drawings depict portions of the toy that form no part of the claimed design.

1 Claim, 10 Drawing Sheets
